UNITED STATES PATENT OFFICE.

CHARLES W. BARTRUM, OF NEWBURGH, NEW YORK, ASSIGNOR TO SWEET-ORR & COMPANY, INCORPORATED, OF NEW YORK, N. Y., A CORPORATION OF NEW YORK.

OVERALLS FOR WOMEN.

1,208,715.

Specification of Letters Patent. Patented Dec. 12, 1916.

Application filed August 12, 1916. Serial No. 114,587.

To all whom it may concern:

Be it known that I, CHARLES W. BARTRUM, a citizen of the United States, residing at Newburgh, in the county of Orange and State of New York, have invented a certain new and useful Improvement in Overalls for Women, of which the following is a full, clear, and exact description.

Women are entering more fully than ever before into those occupations where their common and conventional garb is a hindrance or handicap in regard to their comfort, safety and efficiency. Their skirts especially hamper them in work in the garden, on the farm, and with machinery, and so far as I am aware, they have nothing which would furnish them the comfort and protection which are afforded to men by overalls.

It is believed that overalls for women should be of such character and construction as to enable them to discard all outer garments, such as skirts, petticoats and the like, and excepting a shirtwaist or like body covering, and yet as fully protect their persons from exposure and from soiling incident to the given occupation, and allow perfect freedom of the limbs and body in pursuing such occupation; and it is the object of this invention to provide such a garment.

The invention consists of a two-legged garment, fashioned to fit the waist and to afford abundant room for the seat, hips, and thighs, open at the sides from the waist partway down the legs, closed in the crotch, and finished at the bottoms so as to be capable of being closed about the wearer's ankles or boot tops or gathered up and fastened under the knees after the manner of knickerbockers, the material of the legs falling down over the fastening and producing a skirt effect, and preferably provided with a bib and shoulder straps, as I will proceed now to explain and finally claim.

In the accompanying drawings, in the several figures of which like parts are similarly designated, Figure 1 is a front elevation of one embodiment of the invention, and Fig. 2 is a rear elevation thereof. Fig. 3 is a side elevation showing the garment distended approximately as it will be in use. Fig. 4 is a cross section substantially on line A—B of Fig. 3, on a larger scale to show the upper plaits. Fig. 5 is a front elevation of the upper part of a garment, showing a detach-

able bib. Fig. 6 is a front elevation of the upper part of a garment showing a modification of the bib construction. Fig. 7 is a front elevation showing a bibless garment in part.

The garment comprises the two substantially identical leg portions 1, made very full, and secured at the top to a sectional waistband, 2, 3, the fullness of the legs being reduced at the waist first by proper fashioning of the pattern, and next by plaiting the goods in front, as at 4, preferably using an inverted plait, and at the hips, as at 5 and 6, and at the back, as at 7, using here also by preference an inverted plait. The legs are permanently closed in the crotch, both front and back, by a suitable seam or fell 8, so as to afford the fullest possible protection of the person from exposure. The sides are provided with openings 9 and 10 extending from the waistband downwardly along the hips toward the knees, and these openings are provided with flies 11 and suitable fastenings, such as buttons and buttonholes 12 and 13, by which they may be secured, and so that the back of the garment may be let down as required, or the whole garment may be slipped down. The bottoms of the legs are provided with the box plaits 14 and 15 at front and back, and plaits 16 and 17 on opposite sides of outside side openings 18. Bands 19 are placed at these bottoms into which the plaits are secured. These bands are provided with any suitable means to adjust or fasten the bottoms about the wearer's legs, such as buttonhole tabs 20 and buttons 21. Thus the legs may be made very full from top to bottom, so as to insure a loose, baggy and comfortable fit, permitting perfect freedom of movement of the wearer's body and legs. As shown in full lines Fig. 3, the bottoms may extend to the wearer's shoe tops or ankles, and also, as indicated by dotted lines in the same view, the legs may be gathered up and the bands fastened beneath the wearer's knees, especially when high boots are worn, or the exposure of the lower limbs is immaterial or desirable, and producing a skirt effect or appearance. One or more pockets 22 may be placed upon the garment.

The garment may be made with or without a bib, as desired. As shown in Fig. 7, there is no bib, and as shown in Fig. 6, a

small bib 23 is fastened permanently to the front section of the waistband and has a pocket 24 on it. This bib has suspender ends 25 and these, as shown in Figs. 2 and 5 3 may be provided with buttons 26 at their ends to engage buttonholes 27 in the back section of the waistband; or other fastening means may be substituted which will enable the wearer to put on and take off the garment readily and adjust it as needed. In Figs. 1, 2 and 3, the bib 28 is similar to that shown in Fig. 6, but made wider and fuller, as shown in Figs. 1 and 3, and it may extend rearwardly toward the wearer's 15 sides to afford further protection. As shown in Fig. 5, the bib 29 may be made detachable, and fastened to the front section of the waistband by any suitable fastenings, such as buttons 30 and buttonholes 31.

20 The garment is to be worn with a shirt-waist or other suitable body garment, and without skirts or petticoats, so as to promote the comfort of the wearer and permit perfect freedom of movement. It is made so 25 full as to avoid all immodesty in appearance, and is designed to fully protect the wearer in the pursuit of her work, and preclude any and all accidental exposure of her person.

In the preferred construction of the garment plaits are used throughout to fashion or shape it, and to avoid all elements that would collect dirt and grime, and to present a construction that may be cleaned with facility. Plaits also effect an economy of material and in so doing also reduces the weight of the garment. A belt may be worn with the garment, and especially with one without a bib, and in such cases the waist may be provided, if desired, with belt-loops, as 40 indicated by dotted lines, at 32, Fig. 7.

Any suitable material may be used in the manufacture of the garment, such as khaki, drilling, denim, gingham and the like.

Variations in details of construction to 45 suit individual tastes and for other purposes

are contemplated as within the scope of the invention.

What I claim is:—

1. Overalls for women, having individual leg portions united and permanently closed from front to back throughout the crotch, and full-fashioned in the seat, hips and thighs and down to their bottoms, shaped to fit the waist by means of plaits at front, back and sides, and provided with side openings between the side plaits and fastenings therefor, a waistband divided at the sides so as to open the garment, and having the bottoms similarly plaited and also provided with side openings and fastening bands, whereby the legs may be secured about the wearer's ankles and also just below her knees, the material of the legs at such time falling down over the bottom fastening bands and producing a skirt effect. 65

2. Overalls for women, having individual leg portions united and permanently closed from front to back throughout the crotch, and full-fashioned in the seat, hips and thighs and down to their bottoms, shaped to fit the waist by means of plaits at front, back and sides, and provided with side openings between the side plaits and fastenings therefor, a waistband divided at the sides so as to open the garment, and having the bottoms similarly plaited and also provided with side openings and fastening bands, whereby the garment may be worn with the bottoms extended to the wearer's ankles and also with said bottoms gathered up and fastened beneath the wearer's knees and a bib applied to the front of the garment and having shoulder straps and means to connect them with the back. 75 80

In testimony whereof I have hereunto set my hand this 11th day of August A. D. 1916.

CHARLES W. BARTRUM.
